UNITED STATES PATENT OFFICE.

WILLIAM SAMUEL PRIM, OF NEW YORK, N. Y.

GAS-BURNER.

No. 831,469.

Specification of Letters Patent.

Patented Sept. 18, 1906.

Application filed August 26, 1905. Serial No. 275,878.

To all whom it may concern:

Be it known that I, WILLIAM SAMUEL PRIM, a citizen of the United States, and a resident of the city of New York, borough of 5 Manhattan, in the county and State of New York, have invented a new and Improved Gas-Burner, of which the following is a full, clear, and exact description.

The invention relates to that class of gas-burners commercially known as "incandescent arc lights" or "cluster-burners," in which a number of burners using a Welsbach mantle are grouped together to produce a relatively intense light. The invention is applicable to both interior and exterior illumination.

The principal object of my invention is to provide means for increasing the illuminating power of the gas and rendering the combustion thereof more perfect than in burners now commonly used, to which end I provide a peculiar gas-heater arranged over the burners, from which heater the hot gas is conducted down to the mixing and burning devices.

It is also an object of the invention to improve the devices for regulating and mixing the air and gas so that the most effective results may be obtained.

A further object is to construct the device 30 so that by simple adjustment it may be converted into either an interior or exterior burner—that is to say, a burner adapted for use in or out of doors, as desired.

The invention involves various other features of major or minor importance, all of which will be fully set forth hereinafter, and particularly pointed out in the claims.

Reference is had to the accompanying drawings, which illustrate as an example the 40 preferred embodiment of my invention, in which drawings—

Figure 1 is a perspective view showing the invention adapted for indoor illumination. Fig. 2 is an enlarged sectional view of one of 45 the burners, as shown in Fig. 1. Fig. 3 is a section on the line 3 3 of Fig. 2. Fig. 4 is a detail sectional view of the upper end of the mantle-support showing the manner in which the removable mantle-supports are arranged.

50 Fig. 5 is a detail view of one of the mantle-supports. Fig. 6 is a sectional elevation showing the light adjusted for exterior or out-of-door illumination. Fig. 7 is an enlarged sectional view of the gas check or regulator shown in Fig. 6. Fig. 8 is a detail section on

the line 8 8 of Fig. 6, and Fig. 9 is a detail section on the line 9 9 of Fig. 7.

As best shown in Fig. 6, the gas is supplied to the burner from a tube 10, which extends into a heating-drum 11 and has a stop 12, 60 forcing the gas to pass out of the tube 10 through openings 14 in said tube and into the heating-drum. Below the stop 12 the tube is provided with openings 15, through which the gas re-enters the tube. Said drum 11 has 65 tubes 16 passing through it, these tubes being intended to conduct the hot gases from the burner to the drum, thus thoroughly heating the gas therein. Below the drum 11 the tube 10 supports a spider 17, which is adjustably fastened by set-screw 18. Said spider in turn sustains an annulus 19, with which the shade 20 of the lamp is engaged. The annulus 19 also supports the chimney 21, which is tubular in form and which rises from the 75 annulus, wholly or partly inclosing the drum 11, so as to enforce the heated gases from the burner to pass through, as contradistinguished from around, the drum. The gas supplied through the pipe 10 is therefore 80 caused to circulate through the heating-drum and thence back into the pipe 10, through which the gas passes downward to the burner proper.

According to the arrangement shown in 85 Figs. 1 to 5 the tube 10 passes downward into communication with a tube 22, which is fitted with a valve 23. Preferably this valve has a wheel or its equivalent 24 connected thereto, and to said wheel dependent chains 90 25 are joined, so as to permit opening or closing the valve 23 from below the gas-burner. Said tube 22 extends upward into a gas-chamber 26, which, as shown best in Fig. 8, is preferably of cruciform construction, 95 though this is in no sense essential. The gas-chamber 26 lies alongside of the tube 10 and is braced by means of a clamp 27, engaged with an ear 28, projecting from the gas-chamber. 29 indicates the usual pilot-frame tube 100 which extends from the gas-pipe 22. Rising from the central part of the gas-chamber 26 and screwing into an orifice in the top thereof is a standard pipe or tube 30. Preferably this tube communicates with the interior of 105 the gas-chamber, so as to increase the heating-surface thereof. At its upper end the tube 30 is provided with a head 31, (best shown in Fig. 4,) and is provided with a number of sockets 32. In these sockets the bent 110

ends 33^a of the mantle-supporting arms 33 are loosely engaged. By this arrangement the mantle-supporting arms are removably yet securely held in place. Said arms project outward from the head 31 and carry the mantles 34, as shown in Fig. 1. The tubular part 30 is also important in that it prevents burning away by the heat of the flame.

According to the construction shown in Fig. 1 the burner adapted for exterior illumination is provided with four burners proper, all of the same construction and one of which is illustrated in detail in Fig. 2. Said burners proper comprise a gas-tube 35, communicating with the gas-chamber 26 and formed at its upper end with an outlet-orifice 36, which is commanded by a needle-valve 37. The stem of the valve is threaded in the tube 35 and projects downwardly below the same. Said stem has a head 38, by means of which the valve may be adjusted, and preferably this head is formed with a kerf, facilitating the application of a screw-driver or similar tool. The tubes 35 are bent slightly in the form of an elbow, so as to facilitate the above-described arrangement of the needle-valve 37. Fastened to the upper end of the tube 35 is a foraminous gage 39, which is cylindric in form and loosely receives a similar gage 40, attached to or forming part of the contracted burner-tube 41. As is shown in Fig. 3, a set-screw 42 is provided to limit the relative turning movement of the parts 39 and 40, and by adjusting the gage 40 the orifices in said gage and in the gage 39 may be placed wholly or partly in registry, so as to regulate the supply of atmospheric air drawn into the burner to be mixed with the gas entering the orifice 36. The contracted tube 41 of the burner terminates in an enlarged part 43, over which the usual screen 44 is arranged. The mantle 34 hangs over the burner proper, as will be understood from the prior art and as is illustrated in the drawings.

The heated gas passing from the drum 11 downward through the tube 10 enters the gas-chamber 26 through the tube 22, the valve 23 being open for this purpose. Said gas is maintained in the chamber in a heated condition, the heat being kept up by the juxtaposition of the chamber to the burners and by the heating effect of the before-described tube 30. The check-valves 37 being properly adjusted the heated gas enters the burners through the orifices 36, it being well mixed with the atmosphere in proper proportions, according to the adjustment of the parts 39 and 40, and the mixture passing through the contracted tube 41, after which it expands in the enlarged end 43 and is burned as it is emitted from the gauze cap 44, the heat of combustion raising the heat to incandescent and the cluster of burners giving off an intense light.

The device adjusted for exterior illumina-

tion, as shown in Fig. 6, is provided with five burners instead of four, the fifth burner being screwed into the central portion of the gas-chamber 26 in lieu of the tube 30. (Shown in Fig. 1.) In this case the mantles 34 are sustained by the usual wires 45, which are fastened to the burners, as shown in Fig. 6. Figs. 6, 7, and 9 also illustrate a second manner of constructing the device for regulating the air and gas supply to the burners. As shown best in Fig. 7, each burner has a connection 46 with the gas-chamber 26, and these communicate with two tubular standards 47. (See Fig. 9.) Said tubular standards 47 in turn communicate with a tube 48, in which a plug 49 is screwed. This plug is provided with an orifice 49^a, which is commanded by a needle-valve 50, and said valve has its stem threaded in the lower or bottom wall of the tube 48. Secured to the lower or exposed end of the stem of the valve 50 is a thumb-wheel 51, which lies between the tube-standards 47, so that it may be conveniently grasped by the fingers of the operator. In this manner the thumb-wheel 51 of the valve is exposed and the gas is conducted around the sides thereof through the tubular standards 47. The gas is discharged through the orifice 49^a into the burner, which is essentially the same as previously described.

It is pointed out that the gas and air regulating devices, shown respectively, in Figs. 2 and 7, may be interchanged at will—that is to say, the device shown in Fig. 7 may be applied instead of the device shown in Fig. 1, and the device shown in Fig. 1 may be applied to the device shown in Fig. 7 instead of the mixing and regulating devices there illustrated.

Having thus described the preferred form of my invention, what I claim as new, and desire to secure by Letters Patent, is—

1. The combination of a heater, gas-supply devices leading to and from the same, a burner arranged below the heater and communicating with the gas-supply, an annulus sustained below the heater, a shade supported by the annulus and extending outward and downward therefrom, and a chimney mounted on the annulus and rising from the same, the chimney inclosing the heater.

2. The combination of a heater, a gas-tube leading from the same, a burner located below the heater and communicating with the gas-tube, a spider fastened to the tube below the heater, an annulus sustained by the spider, a shade supported by the annulus and projecting outward therefrom, and a chimney rising from the annulus and inclosing the heater.

3. The combination of a drum, heating-tubes extending vertically through the drum, means for admitting the gas to and conducting it from the drum, and a burner located

under the drum and communicating with the means for conducting the gas from the same.

4. The combination of a drum, a heating device extending through the same, a gas-supply tube extending through the drum, said tube having a stop therein within the drum, an orifice at each side of the stop whereby the gas is introduced into and conducted from the drum, and a burner located below the drum and communicating with the tube passing from the same.

5. A gas-burner having a gas-chamber, a gas-pipe extending through the bottom of said gas-chamber and sustaining the same, a plurality of burners communicating with the gas-chamber, a tubular standard carried by the gas-chamber and communicating with the interior thereof, and mantle-supporting devices carried by said standard.

6. A gas-burner having a gas-chamber, a gas-pipe leading to and sustaining the same, a plurality of mantles communicating with the gas-chamber, a tubular standard rising from and communicating with the chamber, a head carried on the upper end of the standard, the head having sockets therein, and supporting-arms having laterally-bent ends removably fitting in the heads of the sockets.

7. A gas-burner having a gas-supply tube, a needle-valve commanding the same, one end of the tube being closed, and the stem of the needle-valve projecting through said end, and tubular standards located at opposite

sides of the stem of the valve and communicating with said tube, said standards supporting the burner and conducting the gas to the tube.

8. The combination of a drum, a heating-tube extending vertically through it, means for conducting gas to the drum, a gas-tube projecting down from the drum, a burner communicating with the tube below the drum, a downwardly and outwardly projecting shade located between the drum and burner and having a central opening, a chimney rising from the opening in the shade and inclosing the drum, and means for sustaining the shade and chimney.

9. A gas-burner having a gas-tube with a gas-discharge orifice at one end, the other end being closed, a needle-valve commanding said orifice, and having its stem extended through the closed end of the tube, tubular standards located on opposite sides of the stem of the valve and communicating with the gas-tube, and a connection from which the tubular standards extend, said standards conducting the gas from said connections to the gas-tube.

In testimony whereof I have signed my name to this specification in the presence of two subscribing witnesses.
